(57) **CLAIM**

The ornamental design for the lockout device, as shown and described.

DESCRIPTION

FIG. 1 is a top, rear, and right perspective view of a lockout device having an arm and a housing in a first open configuration, according to an embodiment of our new design; FIG. 2 is a top, rear, and left perspective view of the lockout device of FIG. 1;

FIG. 3 is a bottom, rear, and right perspective view of the lockout device of FIG. 1;

FIG. 4 is a bottom, rear, and left perspective view of the lockout device of FIG. 1;

FIG. 5 is a top, front, and right perspective view of the lockout device of FIG. 1;

FIG. 6 is top, front, and left perspective view of the lockout device of FIG. 1;

FIG. 7 is a bottom, front, and right perspective view of the lockout device of FIG. 1;

FIG. 8 is a bottom, front, and left perspective view of the lockout device of FIG. 1;

FIG. 9 is a bottom, front, and left perspective view of the lockout device of FIG. 1, taken at a different angle than FIG. 8;

FIG. 10 is a right plan view of the lockout device of FIG. 1; FIG. 11 is a left plan view of the lockout device of FIG. 1; FIG. 12 is a rear plan view of the lockout device of FIG. 1; FIG. 13 is a front plan view of the lockout device of FIG. 1; FIG. 14 is a top plan view of the lockout device of FIG. 1; FIG. 15 is a bottom plan view of the lockout device of FIG. 1;

FIG. 16 is a top, rear, and right perspective view of the lockout device of FIG. 1, shown in a second closed configuration where the housing is moved axially relative to the arm, relative to the first open configuration.

FIG. 17 is a right plan view of the lockout device of FIG. 1 in the closed orientation;

FIG. 18 is a left plan view of the lockout device of FIG. 1 in the closed orientation;

FIG. 19 is a rear plan view of the lockout device of FIG. 1 in the closed orientation;

(Continued)

FIG. 20 is a front plan view of the lockout device of FIG. 1 in the closed orientation;
 FIG. 21 is a top plan view of the lockout device of FIG. 1 in the closed orientation; and,
 FIG. 22 is a bottom plan view of the lockout device of FIG. 1 in the closed orientation.
 The broken line representations in the views are for illustrative purposes only and form no part of the claimed design. Instead, these broken lines illustrate elements or features that form no part of the design to be patented.
